ELECTRIC HOIST

Humphrey F. Parker, Kenmore, N. Y., assignor
to Columbus McKinnon Chain Corporation,
Tonawanda, N. Y., a corporation of New York

Application April 8, 1942, Serial No. 438,133

3 Claims. (Cl. 254—168)

My invention relates in general to hoists and more particularly to electric hoists of the cable type.

It is well known to those skilled in the art that certain parts of the cable of a hoist receive greater usage and, therefore, are subject to greater wear, particularly where the hoist is used repeatedly to lift the load the same distance. Under such conditions it is desirable to reverse the cable and thus bring a new section into active use. In cases where the wear is such as to require a new cable, the old one may be reversed and used temporarily until a new one can be obtained, thus permitting the hoist to be operated without interruption.

The general object of my invention has been, therefore, to provide a hoist having a cable formed at each end with duplicate anchors, whereby the dead end of the cable may be reversed and anchored to the drum, and the drum end may be attached to the frame, thereby doubling the period of usefulness.

Another object has been to provide fastening means for the anchors, whereby they may be conveniently removed and interchanged.

The above objects and advantages have been accomplished by the device shown in the accompanying drawings, of which:

Fig. 1 is a side elevation of an electric hoist embodying my invention, portions thereof being broken away; and

Fig. 2 is a fragmentary sectional view taken on line II—II of Fig. 1, with a portion of the drum broken away.

My hoist comprises a frame 10 having an intermediate compartment 11 at one end of which is secured a control housing 12, and at the other end of which is secured a gear housing 13. A cover 14 is provided for the control housing, and a cover 15 is likewise provided for the gear housing, whereby the mechanism contained within each of these housings is readily accessible.

The intermediate compartment comprises an outer wall 16 which extends part way around the frame, a motor cover 20 being provided at the side of the frame opposite the wall. The casing and motor cover are so proportioned as to provide a centrally arranged opening 21 through which the cable 22 of my hoist may pass.

The intermediate compartment 11 of my invention houses a drum 23 and a motor 24. The drum is of the usual type and is suitably mounted within the compartment for rotation, and it is formed on its periphery with the usual helical groove 25 for the reception of the cable 22. The

motor 24 is suitably connected to the drum by well known gearing (not shown) mounted within the gear housing 13. The intermediate compartment 11 is provided with an end plate 30 at the control housing end and with an end plate 31 at the gear housing end thereof. These end plates are secured to the outer wall 16 of the compartment in any suitable way, but preferably by welding.

10 A suspending rib 32 extends longitudinally across the compartment and is secured to the end plates 30 and 31 preferably by welding. This rib may be formed of two Z-bars 33 and 34 having their downwardly extending legs 35 interspaced for the reception of the idler sheave 36 which is used when the hoist is designed for four-part rope reeving. The sheave is rotatably mounted upon a shaft 37. The upwardly extending legs 40 of the Z-bars provide suitable flanges for attaching suspending hooks or a trolley. A four-part hook block 41 is provided for the hoist illustrated in the drawings.

15 The cable 22 of my device has an anchor 42 secured to the dead end 43 thereof and this anchor is engaged with an anchor block 44. This block preferably comprises two duplicate parts 45 secured together by a bolt 46 at their outer ends and also secured together and to an anchor bracket 50 by means of a bolt 51. The anchor bracket is preferably formed with an upturned end 52 which engages the lower end of the end plate 31 of the intermediate compartment. The cable passes upwardly over a dead end spool 53 which is carried by the downwardly extending 20 legs 35 of the Z-bars. A screw 54 is passed upwardly through the spool and has its upper end located near the top of the rib whereby the cable will be retained in position thereon. From the spool 53 the cable passes downwardly and over one of the sheaves of the hook block 41, thence upwardly around the idler sheave 36, downwardly around the other sheave of the hook block, and then upwardly to the periphery of the drum. The cable is then wound about the drum and the 25 cable end 55 thereof is secured to the drum. This end of the cable has an anchor 56 similar to or identical with the anchor 42 and this anchor is suitably secured to this end of the cable. This end of the cable may be anchored to the drum in any suitable way and for convenience in the drawings I have shown a well known method in which a threaded recess 60 is provided in the end of the drum at the end of the groove. A recess 61 is also provided which extends from the periphery 60 a sufficient distance. The recess

PREPARATION OF HIGH MOLECULAR
CELLULOSE DERIVATIVES

Siegfried Petersen, Leverkusen-Schlebusch, and
Karl Taube, Leverkusen-I. G. Werk, Germany;

No Drawing. Application July 1, 1941, Serial No.
400,715. In Germany June 6, 1940

10 Claims. (Cl. 18—55)

The present invention relates to the preparation of high molecular cellulose derivatives and to the new products which are obtainable thereby.

In accordance with a known process halogenides of di- or polybasic acids are caused to react upon such cellulose derivatives as still contain free hydroxy groups. The said process results in the forming of a net work between the cellulose molecules. In consequence thereof, the cellulose derivatives become insoluble in organic solvents or at least only capable of being swollen thereby. The said prior known process is accompanied by the disadvantage that during reaction free hydrogen chloride is evolved which may have a breaking-down effect upon the cellulose derivatives. Moreover, in practice the prior known process can be performed only by contacting the ready made shaped articles from such cellulose derivatives either with a solution or with a vapor of carboxylic acid halogenides of the character described. If one would try to dissolve these starting materials in a common solvent they would enter into reaction spontaneously and the reaction product would be precipitated as an insoluble mass which is no longer capable of being molded or only with difficulty.

It is the object of our present invention to obviate these difficulties and to develop a new process which allows one to convert such cellulose derivatives into a higher molecular state, thus improving their stability towards heat and towards organic solvents, without affecting their capability of being molded. Other objects will be apparent from the following description and claims.

In accordance with our present invention esters, ortho-esters or acetals which contain several functional groups which are capable of undergoing a re-esterification or a re-acetalisation reaction at a temperature up to about 220° C. are caused to react at a higher temperature upon cellulose derivatives of the character described. The heating of such starting materials with each other results in the formation of a net work between the cellulose derivatives, alcohols, phenols and so on being split off from the said esters, ortho-esters or acetals and replaced by the cellulose derivatives. The re-esterification and re-acetalisation reactions described occur only at a higher temperature, so that mixtures containing both types of starting materials can be stored, worked and molded in the usual manner. Thus, lacquer solutions can be built up from starting materials of the character described, if desired,

with the addition of softeners, pigments and dye-stuffs. Lacquer solutions of the character described can be applied onto any desired surface and, after drying, baked by exposing the coatings to a temperature of above about 150° C. The coatings thus obtained are characterized by their excellent stability towards organic solvents. Furthermore, solutions containing cellulose derivatives of the character described and esters, ortho-esters or acetals of the type referred to above can be employed for preparing threads, foils or bristles according to a dry or wet spinning process, which after having been exposed to a temperature of say above about 150° C. show an improved stability towards solvents and heat. Finally, our new process can be made use of in the preparation of heat-hardening materials which can be employed for the making of molded articles.

As cellulose derivatives which can be employed for the process of our present invention there may be employed partly alkylated, aralkylated or acylated cellulose derivatives such as cellulose, benzylcellulose, cellulose acetate, cellulose propionate and mixed esters such as aceto butyrate. Suitable esters and ortho-esters and acetals of the character described are sulfurous acid-bis-phenyl ester, oxalic acid-bisphenylester, formic acid-ortho-ethylester, succinic acid-ortho-ethyl-ester, formaldehyde-dibutylacetal, formaldehyde-di(β -chloroethyl)-acetal and acetone-dibutyl-acetal.

The following examples illustrate the invention without restricting it thereto, the parts being by weight:

Example 1

6 parts of acetylcellulose (54% of acetyl) are dissolved in 24 parts of acetone, 12 parts of toluene and 18 parts of glycol-monomethyl-etheracetate. 1 part of sulfurous acid-bisphenylester (see 40 "Liebigs Annalen," vol. 485, page 274, 1931) being dissolved in some acetone is added to the solution. The solution thus prepared is applied or sprayed onto a support; after drying the coating is baked by a short heating to 180-190° C. There is obtained an adhesive coating, which is 45 insoluble in acetone.

Example 2

2 parts of oxalic acid-bis-phenylester being dissolved in a mixture of 4 parts of alcohol and 4 parts of glycolmono-methyl-etheracetate is mixed with a solution of 10 parts of acetyl-cellulose of the composition as described in Example 1. The clear lacquer obtained is applied onto a support and, after drying, baked by a short heating to 55

temperatures of about 180-200° C. It is insoluble in organic solvents and shows a good adhesion on its support.

The acetylcellulose can be replaced by a cellulose-acetobutyrate, which still contains free hydroxy groups.

Furthermore, there can be employed softeners of the type of phthalic acid ester.

Example 3

12 parts of benzylcellulose (54% of benzyl) are dissolved in a mixture of 66 parts of toluene and 22 parts of tetrahydrofuran. After adding 1.5 parts of oxalic acid-bis-phenylester being dissolved in some tetrahydrofuran, the lacquer is applied onto a support as described in the foregoing examples and then baked. It is not as easily soluble in pyridine as is a common benzylcellulose film.

Example 4

In case in Example 1 the sulfurous acid-bis-phenylester is replaced by an equal amount of succinic acid-ortho-ethylester, there is obtained a coating which even at a temperature of 200° C. is stable towards acetone and toluene.

Succinic acid-ortho-ethylester (Bp14mm.=113-116°) can be prepared from succino-bis-imino-ether-chlorohydrate (see "Berichte der deutschen chemischen Gesellschaft," vol. 16, page 361) and alcohol in the cold.

Formic acid-o.ethylester can be used with a similar result.

Example 5

6 parts of acetylcellulose are dissolved in 54 parts of glycol monomethyletheracetate. After the addition of 0.03 part of p-toluene-sulfonic acid and 1 part of formaldehyde-di-(β -chloroethyl)-acetal, being dissolved in the same solvent, the solution is treated as described in the foregoing examples. There is obtained an adhesive coating, which if contacted with acetone is only swollen.

We claim:

1. The process of producing coatings and shaped articles of cellulosic materials which are stable to heat and organic solvents which comprises forming a solution of a cellulosic compound selected from the class consisting of cellulose and its alkylated, aralkylated and acylated derivatives which still contain hydroxyl groups, and of a non-cellulosic polyfunctional compound selected from the class consisting of polyesters of polybasic organic acids, esters of ortho organic acids and acetals

and acetals, in a mutual solvent for said cellulosic compound and said polyfunctional compound, shaping said solution, and thereafter heating the same to effect reaction of the cellulosic compound and the polyfunctional compound with the elimination of a substance selected from the class consisting of alcohols and phenols.

2. A composition of matter adapted for the production of coatings and shaped articles of cellulosic compounds which are stable to heat and organic solvents; comprising a solution of a cellulosic compound selected from the class consisting of cellulose and its alkylated, aralkylated and acylated derivatives which still contain hydroxyl groups, and of a non-cellulosic polyfunctional compound selected from the class consisting of polyesters of polybasic organic acids, esters of ortho organic acids and acetals, in a mutual solvent for the cellulosic compound and the polyfunctional compound.

3. The process as claimed in claim 1 wherein the cellulose derivative is acetyl cellulose.

4. The process as claimed in claim 1 wherein an acetyl cellulose containing free hydroxyl groups is heated to a temperature up to about 200° C. with oxalic acid bisphenyl ester.

5. A composition of matter as defined in claim 2 in which the cellulose derivative is acetyl cellulose.

6. A composition of matter as defined in claim 2 in which the cellulosic compound is acetyl cellulose and the polyfunctional compound is oxalic acid bisphenyl ester.

7. A composition of matter as defined in claim 2, in which the cellulosic compound is acetyl cellulose and the polyfunctional compound is succinic acid orthoethyl ester.

8. A composition of matter as defined in claim 2, in which the cellulosic compound is acetyl cellulose and the polyfunctional compound is formaldehyde-di-(β -chloro-ethyl)-acetal.

9. The process as claimed in claim 1, wherein an acetyl cellulose, containing free hydroxyl groups, is heated to a temperature up to about 200° C. with succinic acid-ortho-ethyl ester.

10. The process as claimed in claim 1, wherein an acetyl cellulose, containing free hydroxyl groups, is heated to a temperature up to about 200° C. with formaldehyde-di-(β -chloro-ethyl)-acetal.
